[57] CLAIM

The ornamental design for football practice placekick holder, as shown and described.

DESCRIPTION

FIG. 1 is a perspective view of a practice placekick holder showing my new design, with a football held thereby and shown in phantom lines for illustrative purposes only;

FIG. 2 is a front elevational view of the holder;

FIG. 3 is a top plan view thereof;

FIG. 4 is a bottom plan view; and

FIGS. 5 and 6 are right and left side elevational views, respectively.

FIG. 1FIG. 3FIG. 6FIG. 2FIG. 5FIG. 4
